(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged view of the claimed portion in FIG. 8 for clarity of illustration.

The evenly dashed broken lines in the figures depict portions of the electronic device which form no part of the claimed design.

The dot-dash broken lines define boundaries of the claimed design and form no part of claimed design.
